UNITED STATES PATENT OFFICE

167,345

BOTTLE

Brooks D. Fuerst, Sylvania, Ohio, assignor to The Grapette Company, Incorporated, Camden,
Ark., a corporation of Arkansas

Application May 20, 1952, Serial No. 19,803

Term of patent 14 years

(Cl. D58—8)

To all whom it may concern:

Be it known that I, Brooks D. Fuerst, a citizen of the United States, residing at Sylvania, in the county of Lucas and State of Ohio, have invented a new, original, and ornamental Design for a Bottle, of which the following is a specification, reference being had to the accompanying drawings, forming a part thereof.

Fig. 1 is a side elevation of a bottle embodying my new design;

Fig. 2 is a top plan view thereof; and
Fig. 3 is a bottom plan view thereof.

I claim:

The ornamental design for a bottle as shown.

BROOKS D. FUERST.
